United States Patent Office

Des. 229,781
Patented Jan. 1, 1974

229,781

APERTURE CARD VIEWER

Thomas C. Laughon, Rochester, N.Y., assignor to
Eastman Kodak Company, Rochester, N.Y.

Filed Sept. 11, 1972, Ser. No. 287,958

Term of patent 14 years

Int. Cl. D16—03

U.S. Cl. D61—1 N

FIG. 1

FIG. 2

FIG. 1 is a top front, and left side perspective view of an aperture card viewer showing my new design;

FIG. 2 is a bottom, rear, and right side perspective view thereof.

I claim:

The ornamental design for an aperture card viewer, substantially as shown.
